CLAIM

The ornamental design for a control lever for watercraft, as shown and described.

DESCRIPTION

FIG. 1 is a perspective view of a control lever for watercraft showing my new design;

FIG. 2 is a front elevational view thereof, the rear view being a mirror image thereof;

FIG. 3 is an elevational view of one side thereof; with the other side view being a mirror image thereof;

FIG. 4 is a top plan view thereof; and,

FIG. 5 is bottom plan view thereof.

The broken lines are for illustrative purposes only and form no part of the claimed design.
